UNITED STATES PATENT OFFICE.

SCIPION POUJOL, OF NEW YORK, ASSIGNOR TO M. H. BIRGE & SONS, OF BUFFALO, NEW YORK.

DESIGN FOR WALL-PAPER.

SPECIFICATION forming part of Design No. 23,624, dated September 4, 1894.

Application filed August 10, 1894. Serial No. 519,976. Term of patent 8½ years.

To all whom it may concern:

Be it known that I, SCIPION POUJOL, a citizen of France, residing at New York, in the county and State of New York, have invented and produced a new and original Design for Wall-Paper, of which the following is a specification.

The design consists of an arrangement of sprays of large flowers and leaves of the poppy, 10 with sprays of small flowers and leaves and fine grass-like sprays drooping or hanging from the sprays of large flowers and leaves, as represented in the accompanying drawing. The border or upper portion of the design is 15 also formed of sprays of large flowers and leaves of the poppy and small grass-like sprays, springing from ornamental scrolls, the space between the under side or bottom of the scrolls and the lower edge of the border being filled with fine filigree work as shown in 20 the drawing.

What I claim is—

The design for wall paper herein shown and described.

Witness my hand this 8th day of August, 25
1894.

SCIPION POUJOL.
